[57] **CLAIM**

The ornamental design for a “lollipop holder”, as shown and described.

DESCRIPTION

FIG. 1 is a perspective view of a lollipop holder, showing my new design;

FIG. 2 is a side elevation view thereof;

FIG. 3 is a top plan view thereof; and,

FIG. 4 is a bottom plan view thereof.

The broken line environmental structure shown in FIG. 1 is for illustrative purposes only and forms no part of the claimed design.
